STERILIZER DOOR

Alfred B. Huston, Erie, Pa., assignor to American Sterilizer Company, Erie, Pa., a corporation of Pennsylvania

Filed June 22, 1964, Ser. No. 376,785

2 Claims. (Cl. 21—91)

ABSTRACT OF THE DISCLOSURE

The invention disclosed herein relates to an autoclave with a door. The door is made of two plates. The outer plate is flat and the inner plate is dished inward away from the outer plate and spacers are provided between the inner and outer plates. The outward surfaces of the outer plate are made of corrosive-resistant material and a seal is provided between the flat surfaces of the door and the autoclave. By having the lining of the autoclave made of a corrosive-resistant material, the remainder of the door can be made of ordinary steel or the like and, therefore, a much more economical door can be constructed.

This invention relates to autoclaves and, more particularly, to the type of autoclave commonly referred to as a sterilizer.

The sterilizer disclosed herein, in combination with a door, provides a structure wherein a relatively economical material can be used on the inner shell of the chamber and door in relatively large machines and a relatively inexpensive material can be used for the outer shell of both sterilizer and door.

It is, accordingly, an object of the present invention to provide an improved combination sterilizer and door.

Another object of the invention is to provide an improved door.

Yet another object of the invention is to provide an autoclave in combination with a door and chamber which is simple in construction, economical to manufacture, and simple and efficient to use.

With the above and other objects in view, the present invention consists of the combination and arrangement of parts hereinafter more fully described, illustrated in the accompanying drawing and more particularly pointed out in the appended claims, it being understood that changes may be made in the form, size, proportions, and minor details of construction without departing from the spirit or sacrificing any of the advantages of the invention.

In the drawing:

FIG. 1 is a side view partly in cross section of a sterilizer.

FIG. 2 is a cross sectional view taken on line 2—2 of FIG. 1.

Now with more particular reference to the drawing, a chamber 10 is shown having a door 11 thereon. The chamber 10 has an inner shell 20 and an outer shell 21 with an end ring 22 holding them in spaced relation. The inner shell 20 may be made of a corrosion resistant material or other suitable material which is generally more expensive than the structural material from which the outer shell 21 and the end ring 22 are made.

A sealing ring 23 is provided which is welded to the inner shell 20 and coextensive with the end ring 22. The sealing ring has axially extending flanges 24 thereon which may receive the arms 31 of the door.

The door is made up of the inner plate 14 and the outer plate 12. The outer plate 12 is flat and made of structural material while the inner plate 14 is dished inwardly toward the inside of the sterilizer chamber. As an alternative to the device shown herein, the plate 12 could be used as an inner plate and the plate 14 as the outer plate.

2

The outer plate 12 and the inner plate 14 are welded together at 26 and the portion of the surface of the inner plate 14 adjacent the outer edge indicated at 27 is generally flat to provide a sealing surface to cooperate with the sealing ring 23.

The center plate 15 is attached to the inner plate 14 by means of studs 28 which can be provided for a conventional steam lock between the two plates.

The door disclosed herein is less expensive to construct and manufacture for high pressure chambers since the thickness of the plates may be reduced because of the truss arrangement of the spacers 19 between the inner plate and outer plate and the dished structure of the inner plate. Thus, the outer plate of the door 12 may be made of a structural material such as structural steel one-quarter inch thick, for example, and the inner plate might be made of nickel clad steel. The box section construction which is, in effect, a truss like arrangement gives the door the required strength.

The foregoing specification sets forth the invention in its preferred practical forms but the structure shown is capable of modification within a range of equivalents without departing from the invention which is to be understood is broadly novel as is commensurate with the appended claims.

The embodiments of the invention in which an exclusive property or privilege is claimed are defined as follows:

1. A door for an autoclave comprising a generally flat outer plate having fastening means thereon to attach i. to said autoclave, an inner plate overlying said outer plate and having peripheral edges coextensive therewith and welded thereto, the surface of the side of said inner plate remote from said outer plate being generally parallel to said inner plate for a substantial distance inwardly from the outer edge thereof providing a generally flat surface and seating means on said flat surface, said inner plate being dished away from said outer plate at the intermediate part thereof, and spacers between said inner and outer plates.
2. In combination, an autoclave and a door, said door comprising a generally flat outer plate having fastening means thereon to attach it to said autoclave, an inner plate overlying said outer plate and having peripheral edges coextensive therewith and welded thereto, the surface of the side of said inner plate remote from said outer plate being generally parallel to said inner plate for a substantial distance inwardly from the outer edge thereof, said inner plate being dished away from said outer plate at the intermediate part thereof, spacers between said inner and outer plates, said autoclave having a door opening at one end and a lining made of corrosion resistant material, a generally flat, outwardly facing surface of said corrosion resistant material around said door opening, sealing means between said flat surface of said door and said end of said autoclave, and means on said autoclave to engage said fastening means on said door.
